US0D1096557S

(12) **United States Design Patent** (10) **Patent No.:** **US D1,096,557 S**
(45) **Date of Patent:** **** Oct. 7, 2025**

(54) **DISPLAY FOR AUTOMOBILE INTERIOR**

(71) Applicant: **LG ELECTRONICS INC.**, Seoul (KR)

(72) Inventors: **Byunglok Jeon**, Seoul (KR); **Hansoo Kim**, Seoul (KR); **Sanghyeon Son**, Seoul (KR); **Inkoo Shim**, Seoul (KR); **Jinhee Kim**, Seoul (KR); **Byungkyu Kim**, Seoul (KR); **Sewon Chun**, Seoul (KR)

(73) Assignee: **LG ELECTRONICS INC.**, Seoul (KR)

(**) Term: **15 Years**

(21) Appl. No.: **35/521,273**

(22) Filed: **Apr. 8, 2024**

(80) **Hague Agreement Data**

Int. Filing Date: **Apr. 8, 2024**

Int. Reg. No.: **DM/237481**

Int. Reg. Date: **Apr. 8, 2024**

Int. Reg. Pub. Date: **Jun. 14, 2024**

(30) **Foreign Application Priority Data**

Nov. 30, 2023 (KR) 30-2023-0048448

(57) **CLAIM**

The ornamental design for a display for automobile interior as shown and described.

DESCRIPTION

1. Display for automobile interior

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

1.15 : Perspective

1.16 : Front

1.17 : Back

1.18 : Left

1.19 : Right

1.20 : Top

(Continued)

1.21 : Bottom**1.22** : Perspective**1.23** : Front**1.24** : Back**1.25** : Left**1.26** : Right**1.27** : Top**1.28** : Bottom

Reproductions **1.1** to **1.7** show the claimed design in the first position; Reproductions **1.8** to **1.14** show the claimed design in the second position; Reproductions **1.15** to **1.21** show the claimed design in the third position; and Reproductions **1.22** to **1.28** show the claimed design in the fourth position.

1 Claim, 28 Drawing Sheets
